Fig. 8.

Fig. 6.

Fig. 9.

FIG. 1 is a side elevational view of a frozen confection showing my new design;

FIG. 2 is a top plan view of the frozen confection as shown in FIG. 1;

FIG. 3 is a bottom view of the frozen confection shown in FIG. 1;

FIG. 4 is a side elevational view of another embodiment of the frozen confection of FIG. 1, on a smaller scale, having three swirls;

FIG. 5 is a top plan view of the frozen confection shown in FIG. 4;

FIG. 6 is a bottom view of the frozen confection shown in FIG. 4;

FIG. 7 is a side elevational view of a further embodiment of the frozen confection shown in FIG. 1, on a smaller scale, having four swirls;

FIG. 8 is a top plan view of the frozen confection shown in FIG. 7; and

FIG. 9 is a bottom view of the frozen confection shown in FIG. 7.

I claim:

The ornamental design for a frozen confection, as shown and described.
